CLAIM

The ornamental design for the reduced pressure therapy device, as shown and described.

DESCRIPTION

FIG. 1 is a rear perspective view of a reduced pressure therapy device showing my new design;

FIG. 2 is a front elevation thereof;

FIG. 3 is a rear elevation thereof;

FIG. 4 is a right side elevation thereof, the side opposite being a mirror image; and,

FIG. 5 is a top plan view thereof, the side opposite being a mirror image.

The broken lines which define the bounds of the claimed design form no part thereof.
